CIGARETTE PROCESSING MACHINE

Guillermo Solomon, Santiago, Dominican Republic

Application February 20, 1935, Serial No. 7,417

12 Claims. (Cl. 131—39)

This invention relates to a machine for processing cigarettes, the processing consisting in compacting the tobacco filler of each cigarette, so that the filler will terminate short of one end of the cigarette wrapper, and the processing to constitute a step in the manufacture of cigarettes.

The principal object of the invention is the processing of cigarettes so that each has a mouth end consisting of an empty or unfilled wrapper portion, to eliminate the objectionable particles of tobacco which find their way into the mouth of the smoker, as occurs in smoking a cigarette with a fully filled wrapper, or one in which the tobacco filler extends entirely from one end of its wrapper to the other.

The invention resides in a machine having the features as hereinafter described and claimed and illustrated in the accompanying drawings, in which

Fig. 1 is a vertical section and part elevation of a machine embodying the features of the invention, the section being taken approximately on the line 1—1 of Fig. 2;

Fig. 2 is a section on the line 2—2 of Fig. 1;

Fig. 3 is a longitudinal section through a cigarette before being processed;

Fig. 4 is a view similar to Fig. 3 showing the cigarette after being processed.

Referring now more particularly to the drawings, it will be apparent that the machine includes cigarette feeding means designated generally by the reference numeral 10. This feeding means includes a rotor 11 mounted for rotation within a casing 12 supported by legs 13. The rotor 11 is keyed fast to a horizontal shaft 14, as at 15. The shaft 14 has its opposite ends journaled in bearings 16 respectively on opposite side walls respectively of the casing 12. The periphery of the rotor 11 has cigarette receiving grooves 17 therein spaced equi-distantly, and each being disposed parallel to the axis of rotation provided by the shaft 14. The feeding means also includes a hopper 18 secured to or formed integral with the casing 12 as shown, with the lower discharge end in communication with the interior of the casing 12 so as to feed one cigarette in each of the grooves 17 of the rotor 11, under the action of gravity, as the rotor 11 is in motion. The cigarettes are designated C. The cigarettes may be deposited into the hopper 18 in any suitable manner.

The cigarettes are fed successively one at a time into a cigarette guide tube 20. This is accomplished by reason of the fact that the tube is secured to the casing 12 in communication with

the interior thereof, the communication being established at one end of the tube 20 as shown in Fig. 1. The tube 20 has an air inlet end 21, and a cigarette outlet end 22, the latter being flared to facilitate the discharge of the cigarettes. Each of the cigarettes will be fed into the tube 20 lengthwise of the latter so as to be projected or "shot" in this position through the tube 20 and out of its outlet end 22.

In order to project or "shoot" the cigarettes through the tube 20 as they are fed by the rotor 11, there is provided a blower or blast fan 23, and a connection 24 between the periphery of the fan casing and the inlet end 21 of the tube constituting means in the form of a nozzle for delivering air under pressure from the fan into the tube 20, which projects each cigarette along the tube out of its groove 17 away from the rotor 11. A connection 25 between the periphery of the casing of the fan, and the tube 20, beyond the rotor 11, constitutes a nozzle to deliver compressed air from the fan into the tube, to project or "shoot" each cigarette after leaving the rotor 11 through the tube 20 and out of its outlet end against a stop 26 held in various adjusted positions in spaced relation to the outlet end 22 of the tube. In the present instance the stop 26 is secured in adjusted positions on the support 27 secured to the tube. A set screw 28 carried by the stop 26 engages the support 27 to fix the stop in the desired position. The stop 26 presents a flat face 29. Each cigarette, as it leaves the tube 20 strikes the face 29, and as a consequence the tobacco filler will be compacted to such an extent that the filler will terminate short of one end of the cigarette wrapper. In other words, each cigarette will have a mouth end consisting of an empty or unfilled wrapper portion, as shown in Fig. 4. The tobacco filler of the cigarette is designated 30, the wrapper 31, and the mouth end 32.

The rotor 11 and the fan may be driven by any suitable means, and in the present instance use is made of an electric motor 35, whose shaft is coupled with the fan shaft 36. Motion is transmitted from the shaft 36 to the rotor shaft 14, by the beveled gear 37 on the shaft 36, a beveled gear 38 which meshes with the gear 37, said gear 38 being mounted on a shaft 39 supported by suitable bearings 40 respectively on the fan casing and the casing 12. The shaft 39 has a worm 41 which meshes with a worm gear 42 keyed to the shaft 14.

Each of the connections 24 and 25 has a regulating valve 43 therein to regulate the velocity and pressure of the air.

The present machine may constitute an adjunct of a cigarette manufacturing machine, or a cigarette packing machine, or it may be used as a distinct entity for processing cigarettes before they are packed in their original packages.

I claim:

1. In a machine of the character described, a tube, a stop arranged in fixed relation to the outlet end of the tube, and means to shoot cigarettes one at a time lengthwise through said tube against said stop, to compact the tobacco filler, so that it will terminate short of one end of the cigarette wrapper.
2. In a machine of the character described, a tube, a stop fixed in relation to the outlet end of the tube and providing a flat face perpendicular to the longitudinal axis of the tube, and means to shoot cigarettes one at a time lengthwise through said tube against said flat face, to compact the tobacco filler, so that it will terminate short of one end of the cigarette wrapper.
3. In a machine of the character described, a tube, a fixed stop arranged in spaced relation to the outlet end of the tube, and means to shoot cigarettes one at a time lengthwise through said tube against said stop, to compact the tobacco filler, so that it will terminate short of one end of the cigarette wrapper.
4. In a machine of the character described, a tube, means for alining one cigarette at a time lengthwise of the tube with respect to the inlet end thereof, a fixed member arranged in spaced relation to the outlet end of the tube, and means to send each cigarette alined as aforesaid, through the tube against said fixed member, to compact the tobacco filler, so that it will terminate short of one end of the cigarette wrapper.
5. In a machine of the character described, a tube, a rotor having cigarette receiving grooves in the periphery thereof for alining one cigarette at a time lengthwise of the tube with respect to the inlet end thereof, a fixed member arranged in spaced relation to the outlet end of the tube, and means to send each cigarette alined as aforesaid, through the tube against said fixed member, to compact the tobacco filler, so that it will terminate short of one end of the cigarette wrapper.
6. In a machine of the character described, a tube, a stop arranged in fixed relation to the outlet end of the tube, and means to shoot cigarettes one at a time lengthwise through said tube against said stop, to compact the tobacco filler, so that it will terminate short of one end of the cigarette wrapper, said means communicating with said tube to force air therein for the aforesaid purpose.
7. In a machine of the character described, a tube, a rotor having cigarette receiving grooves in the periphery thereof parallel to its axis of rotation, for the purpose of alining one cigarette at a time lengthwise of the tube with respect to the inlet end thereof, a fixed member arranged in spaced relation to the outlet end of the tube in alinement therewith, a blower communicating

with the inlet end of the tube to force air therein to project each cigarette from the rotor through the tube against said fixed member, to compact the tobacco filler, so that it will terminate short of one end of the wrapper, and means to operate 5 the rotor and blower.

8. In a machine of the character described, a rotor adapted for feeding cigarettes successively one at a time into a predetermined position, means co-operating with the rotor to project 10 each cigarette endwise from said position, and means against which each projected cigarette strikes, to compact the tobacco filler thereof, so that the filler will terminate short of one end of the cigarette wrapper.

9. In a machine for compacting the tobacco filler of cigarettes, so that the filler of each cigarette will terminate short of one end of the cigarette wrapper, a cigarette guide tube, a fixed member arranged in spaced relation to the outlet 20 end of the tube against which the cigarettes strike endwise to compact the tobacco filler, air blast means communicating with the tube axially thereof at a point remote from its outlet end, and means for feeding the cigarettes one at a 25 time to said tube between the point of entry of the air and the outlet end of the tube, so as to slide endwise in said tube under the action of the air blast.

10. In a cigarette processing machine, a cigarette guide tube, means to feed one cigarette at 30 a time into the tube lengthwise thereof, air blast means, a connection between the air blast means and one terminal of the tube to deliver air thereto to project each cigarette along the 35 tube away from the feeding means, and a second connection between the air blast means and the tube to deliver air thereto, to project each cigarette along said tube after leaving said feeding means.

11. In a cigarette processing machine, a cigarette guide tube, means to feed one cigarette at a time into the tube lengthwise thereof, air blast means, a valved nozzle between the air blast means and one terminal of the tube to deliver 45 air thereto to project each cigarette along the tube away from the feeding means, and a second valved nozzle between the air blast means and the tube to deliver air thereto, to project each cigarette along said tube after leaving said feeding 50 means.

12. In a machine of the character described, a casing, a grooved rotor operable in said casing for feeding cigarettes successively one at a time into a predetermined position with respect to 55 said casing, means connected with said casing to project each cigarette endwise from said position, and means against which one end of each projected cigarette strikes, to compact the tobacco filler thereof, so that the filler will terminate 60 short of one end of the cigarette wrapper.

G. SOLOMON.
